(57) **CLAIM**

The ornamental design for a kitchen ventilation hood, as shown and described.

DESCRIPTION

FIG. 1 is a top, front, perspective view of a kitchen ventilation hood showing our new design;

FIG. 2 is a front view thereof;

FIG. 3 is a top view thereof;

FIG. 4 is a bottom view thereof;

FIG. 5 is a left side view thereof, with the right side view thereof being a mirror image; and,

FIG. 6 is a bottom perspective view thereof.

The broken lines in the drawings depict parts of the kitchen ventilation hood that form no part of the claimed design.
